EDMOND QUERU, OF NEW YORK, N. Y.

Letters Patent No. 65,270, dated May 28, 1867.

IMPROVED BOX FOR PUTTING UP TOOTH-POWDERS.

The Schedule referred to in these Letters Patent and making part of the same.

TO ALL WHOM IT MAY CONCERN:

Be it known that I, EDMOND QUERU, of the city of New York, and county and State of New York, have invented certain new and useful improvements in boxes adapted especially for containing dentophile, but which may be used for containing other tooth-powders, or articles which are liable to be occasionally exposed to moisture; and I do hereby declare that the following is a full and exact description thereof.

The principal material of my boxes is wood. I prefer a hard, close-grained wood, but the soft woods may answer a good purpose, and with either material the boxes are much lighter and cheaper than any before known to me which are equally desirable in other respects.

I will first describe what I consider the best means for carrying out my invention, and will afterwards designate the points which I believe to be new. The accompanying drawings form a part of this specification.

Figure 1 is an edge view showing the manner in which the sides are cut and bevelled.

Figure 2 is a plan view of the former.

Figure 3 shows the manner in which the sides are piled when first glued.

Figure 4 shows the manner in which the sides of the boxes when glued are piled.

Figure 5 is a plan of the bottom and cover of the box.

Figure 6 shows in a longitudinal section the bottom glued to the sides.

Figure 7 is a cross-section of the box complete.

Figure 8 is an elevation of the box, the cover lifted.

Figure 9 shows another form of the boxes.

Similar letters of reference indicate corresponding parts in all the figures.

I take the best of well-seasoned wood, very smoothly sawed or planed to the thickness and width desired, and of any length which may be conveniently obtainable, and introducing it in a proper machine, not represented, cut it across in V-shaped scores, as indicated in the figs. 1 and 2. These scores are of a depth exactly equal to the thickness of the material. The effect is to cut off the pieces with a bevel at each end. I take these pieces and apply strong glue to one bevelled edge of each. I then apply the glued edges of two pieces together and pile them in positions where they will support each other, as indicated in fig. 3, and allow them to be hardened. Having manufactured a sufficient number of these parts I apply glue to the remaining bevelled edges, and apply these compound parts together, and place those away, as indicated in fig. 4. I manufacture two rectangular pieces of the same or of a different wood, of the same or different thickness, and of an area a little greater than the rectangular frame already described. These last pieces serve for the top and bottom. I apply glue to the entire lower edge of one of the rectangular frames, and press it upon the piece which is to form the bottom. When this is hard I take the piece which is to form the top, and holding it in position on the top of the box, glue a strip of muslin or of tape along one side, so as to be glued partly upon the sides, and partly upon the top. When this is hard, and my box filled with dentophile or other material, I paste a strip of paper along the remaining edges, and paste one edge of the paper upon the sides, the other edge upon the cover.

Referring to the drawings, A B C D are the sides pieces; E E are glued joints between them; F is the bottom piece; G is the glued joint between; H is the cover; I is the muslin; J K are the glued joints between; L is the strip of paper; M N are the pasted joints, the joint M being the union of the paper with the cover, and the joint N being the union of the paper with the sides.

My box is opened by simply dividing the paper L between the joints M and N, and leaving the muslin or tape I connected by the glue J K to serve as a permanent hinge. The result is a box, not fragile like china or glassware, nor so easily destroyed by water as pasteboard, but sufficiently strong and water-proof for all toilet purposes, and well adapted to contain tooth-powders, cosmetics, etc. Fig. 9 indicates a different form of the invention which will be readily understood from the drawings. The pieces are applied together in the same manner, and with the same material as above described, but in the previous preparation of the strips of wood for the sides, they are rebated, as indicated, and narrow pieces are attached to the cover and adapted to match the rebates on all sides. The closing is effected by the same means as above described. This form of the invention is more labored and more costly than the other. I prefer the one just described for general purposes.

Rich varieties of wood, or staining, may be employed, so also may veneering, machine carving, gilding, and other approved ornamentation for the surfaces of my boxes.

Having now fully described my invention, what I claim as new, and desire to secure by Letters Patent, is as follows:

1. I claim the toilet-box, constructed of the material and in the manner substantially as herein set forth.
2. I claim securing the cover thereon, by the fibrous hinge I J K, and seal L M N, substantially as and for the purpose herein set forth.

In testimony whereof I have hereunto set my hand in the presence of two subscribing witnesses.

EDMOND QUERU.
